UNITED STATES PATENT OFFICE

CHARLES SILVERMAN, OF PROVIDENCE, RHODE ISLAND

DESIGN FOR A COLLAR HOLDER

Application filed November 19, 1932. Serial No. 46,075. Term of patent 3½ years.

To all whom it may concern:

Be it known that I, CHARLES SILVERMAN, a citizen of the United States, residing at Providence, in the county of Providence and State of Rhode Island, have invented a new, original, and ornamental Design for Collar Holders, of which the following is a specification, reference being had to the accompanying drawing, forming part thereof.

I claim:

The ornamental design for a collar holder, as shown.

CHARLES SILVERMAN.
